US00D997025S

(12) **United States Design Patent** (10) **Patent No.:** **US D997,025 S**
(45) **Date of Patent:** **** Aug. 29, 2023**

(54) **DECORATIVE ELEMENT FOR JEWELRY**

(71) Applicants: **Rachel Aschendorf**, New York, NY (US); **Anna Amsalem**, New York, NY (US)

(72) Inventors: **Rachel Aschendorf**, New York, NY (US); **Anna Amsalem**, New York, NY (US)

(**) Term: **15 Years**

(21) Appl. No.: **29/788,542**

(22) Filed: **Jun. 18, 2021**

(51) **LOC (14) Cl.** **11-01**

(52) **U.S. Cl.**

USPC **D11/91**

(58) **Field of Classification Search**

USPC D11/1-2, 26-30, 89-92

CPC A44C 17/04

(57) **CLAIM**

The ornamental design for a decorative element for jewelry, as shown and described.

DESCRIPTION

FIG. 1 is a front bottom right perspective view of the decorative element for jewelry, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings depict portions of the decorative element for jewelry that forms no part of the claimed design.

1 Claim, 5 Drawing Sheets
